UNITED STATES PATENT OFFICE

150,626

DESIGN FOR A PARABOLIC REFLECTOR FOR MICROWAVE ANTENNAE

Donald S. Kennedy, North Scituate, Mass.

Application June 20, 1947, Serial No. 139,836

Term of patent 14 years

(Cl. D26—14)

To all whom it may concern:

Be it known that I, Donald S. Kennedy, a citizen of the United States and a resident of North Scituate, county of Plymouth, and State of Massachusetts, have invented a new, original, and ornamental Design for a Parabolic Reflector for Microwave Antennae, of which the following is a specification, reference being made to the accompanying drawing, forming part thereof.

In the drawing:

Fig. 1 is a perspective view of a parabolic reflector for microwave antennae, showing my new design;

Fig. 2 is a perspective view of my novel design from the concave side; and

Fig. 3 is a plan view showing an enlarged detail of the expanded metal grid structure placed along the entire concave surface of my novel design.

I claim:

The ornamental design for a parabolic reflector for microwave antennae, as shown.

DONALD S. KENNEDY.
